UNITED STATES PATENT OFFICE.

WINFIELD S. POTTER, OF PITTSBURGH, PENNSYLVANIA.

INGOT-MOLD.

1,278,206.

Specification of Letters Patent. Patented Sept. 10, 1918.

Application filed January 26, 1915. Serial No. 4,429.

To all whom it may concern:

Be it known that I, WINFIELD S. POTTER, a citizen of the United States, residing at No. 1317 Highland ave., city of Pittsburgh, 5 county of Allegheny, State of Pennsylvania, have invented certain new and useful Improvements in Ingot-Molds; and I do hereby declare the following to be a full, clear, and exact description of the invention, such as 10 will enable others skilled in the art to which it appertains to make and use the same.

My invention relates to certain new and useful improvements in ingot molds for the forming of ingots of manganese steel and 15 other steels, said molds being of the kind known as inverted molds, that is to say, ingot molds whose interior cross section increases from the bottom upwardly toward the zone of the sink head or riser.

20 In the accompanying drawing,

Figure 1 represents a vertical sectional view of an ingot mold embodying the invention;

Fig. 2 represents, on a larger scale, a sectional view of a portion of the bottom joint thereof;

Fig. 3 represents a vertical sectional view showing a modification;

Fig. 4 represents a top plan view thereof.

Similar letters of reference indicate similar parts throughout the several views.

Referring to the drawing, *a* indicates an iron bottom plate upon which the inverted ingot mold *b* is supported. The interior of the mold may be of any suitable dimensions according to the size of the piece to be manufactured. In order to hasten the freezing of the lower portion of the ingot, the walls of the mold are preferably made thickest at the bottom, and, on this account, taper from the bottom upwardly, as indicated,—a suitable taper being say one inch on each side for an ingot which is twenty inches square at the bottom and of the relative height shown in the drawing, so that where the taper ends, at a height shown by the letters *d*, *d*, the ingot may have, for instance, a cross-sectional area corresponding to 22 inches square.

The iron bottom plate *a* is provided with a projection *h*, whose edge periphery co-operates with the inner edge of the lower opening of the mold, whereby the mold may fit snugly over and upon the said projection *h*. In order that the parts may fit with a degree of snugness satisfactory in practice, the projection *h* is preferably rounded off, as shown,

and the co-operating inner edge of the lower opening of the mold is given a corresponding curvature. The purpose of thus providing for a suitably close fit between the projection *h* and the inner edge of the lower opening of the mold is to insure against the formation of a fin of steel at the smaller and lower end of the poured ingot, which fin, if thick, would prevent the subsequent stripping of the mold from the ingot, in which event, both the mold and the ingot would have to be scrapped. By providing the projection *h*, the finning and locking of the ingot in the mold is prevented, and it becomes entirely feasible to strip the mold from the ingot by means of the ordinary large mechanical strippers, such as are used for stripping molds of the ordinary type.

As a further precaution, a soft plastic roll 75 of luting material, preferably of fire clay made plastic by oil, or a mixture of fire clay and sand, made plastic by oil may be placed upon the upper surface of the bottom plate, so as to encompass the projection *h*; whereupon, when the mold is set down upon the bottom plate, the roll of luting material will be flattened out into a thin sheet, as indicated at *c*. In general, however, this luting material will be necessary only when the opposed 80 surfaces of the mold and bottom plate have become rough through use, for the reason that the mold, whose centering upon the bottom plate is facilitated by the projection *h* will make a sufficiently snug fit therewith to 85 obviate any substantial finning.

At the upper part of the mold, that is to say, at the zone of the riser, a refractory head is provided, which is preferably formed as follows: Bent rods *t*, or their equivalents, 95 may be used as a crab or frame about which a core of dry sand mixture, or ganister mixture is molded, and then dried in any suitable core oven. The frame referred to is employed as a reinforcement of the core and is 100 preferably made to project slightly, as shown, both at the top and at the bottom, so that when the core is placed on the corresponding ledge of the ingot mold, as shown in Figs. 1 and 3, the weight of the core, together with any 105 weights which may rest upon the core is carried to the ledge of the ingot mold, by the bent rods *t* or their equivalent.

When the refractory head *e* is placed in the ingot mold, a small quantity of any suitable luting material, as, for instance, a mixture of fire clay and oil, is placed on the

ledge upon which the rods *t* rest, so as to prevent finning at this point.

The refractory head *e* as shown, preferably tapers inwardly and upwardly along its interior walls which may terminate in an upper opening preferably somewhat smaller than the cross-section at *d*, *d*. This refractory head serves also for the reception of a body *f* of charcoal or other fuel to be placed on top of the metal, after the ingot has been poured so as to keep the metal in the sink head or riser from freezing until after the metal has frozen in the main body portion of the mold. Or some other suitable means may be employed for retarding the radiation of heat from the top of the hot ingot, as, for instance, a body of hot slag, or a body of hot dry lime may be substituted for the charcoal or other fuel *f*.

In order to hold down the refractory head *e*, and particularly to prevent the cutting or breaking down of the inner edges of the refractory material by the liquid steel during the pouring of the ingot, it is desirable to place a cover upon the refractory head. For instance, as shown in Fig. 1, a cast iron cover *s* may be employed, which will rest upon the projecting upper bends of the rods *t* or their equivalents. Or, instead of the cover *s*, plates *s' s'* may be employed as indicated in Figs. 3 and 4.

The plates *s' s'* may be held in position, during the pouring of the ingot by means of wedges or keys *n* resting upon cross plates *s²*, and engaging with steel hooks *v*, or the like, which hooks may be cast into the upper part of the main body portion of the metal mold.

In stripping the ingot from the mold, it will be desirable to remove the cover *s*, or the plates *s' s'* as the case may be, from the mold, in order that there may be no interference with the progress of the stripping operation.

In Fig. 1, the ingot mold is shown as provided with the usual downwardly inclined lugs *m* for lifting the mold with the ingot. The mold and ingot are then lowered, in such manner that, in the lowering operation, the ingot will come in contact with a block thereby forcing it upward out of the mold so that it may be seized by crane tongs, whereupon it is placed in the soaking pit or heating furnace for the subsequent heating operation, preparatory to rolling or otherwise forming or shaping it.

In the form of mold shown in Fig. 3, the lugs *m'* are inverted. In such case, in order to strip the mold, crane tongs lift the mold and ingot, taking hold under the inverted lugs, the mold and ingot, are then lowered upon a plate which is provided with a circular aperture through which a hydraulic plunger is capable of being moved upwardly, thereby forcing the ingot out of the mold.

While in this position, the ingot is seized by the crane tongs and removed from the mold, and may then be placed upon a truck to convey it to the soaking pit. When the mold of Fig. 3 is placed upon the plate equipped with the hydraulic plunger as described, the mold is seized on opposite sides by means of rocking links, which, swinging toward the center, fall over the inverted lugs. When the hydraulic plunger pushes upwardly on the middle of the bottom of the ingot, these swinging links, which have a fixed point of support, hold the mold down against the plate. The stripping action is therefore positive and enables a force to be applied through the plunger which is, if necessary, greater than the force required to lift the ingot and the mold.

The use of ingot molds of the kind herein described and shown is found to be particularly advantageous in the casting of ingots designed for the production of rails or like shapes from manganese steel, the resultant ingot being practically free from slag and devoid of pipe, and the avoidance of finning permitting the practical and commercial employment of the inverted mold during a long continued period of use.

As a means of effecting an economy in the maintenance of bottom plates, the bottom plate may be made in two parts as indicated by the dotted line *w w*, Fig. 2. The removable portion above the dotted line *w w* being renewed when the cutting action of the liquid metal striking on its upper surface has, by continued use, cut through the removable portion.

What I claim is:

1. An ingot mold for the casting of ingots of manganese steel and other steels, comprising a main body portion or mold proper of the "inverted mold" type and a bottom plate therefor provided with a rounded-off centering projection making a snug fit with the inner edge of the lower opening of the said main body portion, the inner edge of said lower opening of the main body portion being curved to fit the said rounded-off projection.

2. An ingot mold for the casting of ingots of manganese steel and other steels, comprising a main body portion or mold proper of the "inverted mold" type, a bottom plate therefor provided with a centering projection having a rounded-off edge periphery adapted to fit within the lower opening of the said main body portion, the inner edge of said lower opening being formed to fit over and upon the rounded-off edge periphery of said projection.

3. An ingot mold for the casting of ingots of manganese steel and other steels, comprising a main body portion or mold proper of the "inverted mold type," a bottom plate therefor provided with a rounded-off cen-

tering projection making a snug fit with the inner edge of the lower opening of the said main body portion, and a layer of plastic material sealing the joint between the bottom plate and mold, the inner edge of said lower opening of the main body portion being curved to fit the said rounded-off projection.

4. In an ingot mold of the kind described, 10 a refractory head consisting of a baked core of refractory material, containing a reinforcing frame projecting through the lower surface of the refractory head and adapted to rest upon a corresponding ledge of the main body portion of the mold.

15 5. In an ingot mold of the kind described,

a refractory head consisting of a baked core of refractory material, containing a reinforcing frame projecting from the lower surface of the refractory head and adapted to 20 rest upon the corresponding ledge of the main body portion of the mold, and a cover plate or plates for holding the refractory head in place during the pouring of the ingot.

25 In testimony whereof I affix my signature, in presence of two witnesses.

WINFIELD S. POTTER.
